Primary Examiner — Ricky Pham(74) *Attorney, Agent, or Firm* — Alleman Hall McCoy Russell & Tuttle LLP(57) **CLAIM**

The ornamental design for a kitchen drawer accessory, as shown and described.

DESCRIPTION

FIG. 1 is a perspective view of a design for a kitchen accessory according to the present disclosure.

FIG. 2 is a second perspective view of the kitchen drawer accessory of FIG. 1.

FIG. 3 is a front view of the kitchen drawer accessory of FIG. 1; and,

FIG. 4 is a bottom-rear perspective view of the kitchen drawer accessory of FIG. 1.

The solid lines in FIGS. 1–4 illustrate a kitchen drawer accessory according to the present disclosure. The broken lines form no part of the claimed design. Rear, top, bottom, left, and right views are not shown as they do not show any additional claimed features.
